CLAIM

The ornamental design of a handle for a kitchen utensil—whisk, as shown described.

DESCRIPTION

FIG. 1 is a top plan view of a handle for a kitchen utensil—whisk showing my new design, the whisk is shown in broken lines for illustrative purposes only and forms no part of the claimed design;

FIG. 2 is a left side elevation view thereof, the opposite side being a mirror; and,

FIG. 3 is an end view thereof.
